DISMOUNTABLE BARRACK

Emile Beaud, Albeuve, Fribourg, Switzerland, assignor to house Maurice Beaud & Fils, Albeuve, Switzerland, a firm of Switzerland

Application May 26, 1944, Serial No. 537,401
In Switzerland May 3, 1943

4 Claims. (Cl. 20-2)

1

This invention relates to barracks which can be taken to pieces. Different constructions of dismountable wooden barracks have become known up to date but the same are either not assembled solidly enough or the parts are combined to a very stable construction which, however, can only with difficulty be taken to pieces. Besides this, there are too many details.

The invention remedies these inconveniences in that the wall of the barrack consists of elements capable of being fitted into one another. These elements have a frame and a panel carried by the same; this panel may also comprise a window or a door. These elements have a very great supporting capacity and can very easily be taken to pieces owing to the fact that they can be fitted into one another by means of groove and tongue. The erection of a wall is carried out very simply in that between the corner posts of the barrack one element after the other can be fitted into one another. The corner posts prevent the walls from going to pieces.

The roof, too, consists of elements which are detachably connected with one another by clamping pieces. It can be suspended on lists fixed to the upper purlins.

The accompanying drawing illustrates, by way of examples, different embodiments of the object of invention.

Fig. 1 is a horizontal section through the ends of two wall elements connected with each other by means of groove and tongue.

Fig. 2 is a section corresponding to that shown in Fig. 1, the one element, however, comprising a window.

Fig. 3 is a vertical section showing portions of the wall, roof and sill.

Fig. 4 illustrates a first and

Fig. 5 a second manner of connecting the roof elements with one another.

Fig. 6 shows the connection of two roof elements at the gable.

Fig. 7 is a horizontal section view through a corner post.

The frame of the elements is formed of two vertical parts 1 (right part 1 in Fig. 1 and left part 1 in Fig. 2 belong to the same element), a lower horizontal part 5 (Fig. 3) and an upper horizontal part 29 (Fig. 8). This frame 1, 5, 1, 29 carries a panel formed of boards 3. On the right side of Fig. 2 the panel consists of portions 4 and the window 30. The tongues 2 are glued to one element and, the elements being assembled, enter grooves 31 of the adjacent element. The lower frame part 5 is guided in a groove of the sill 6 55

2

(Fig. 3), the upper part 29, however, in a groove of the purlin 26 in order to secure the wall against lateral deflection. The erection of a wall, therefore, takes place in a simple manner by fitting 5 groove and tongue 31, 32 into one another. The corner posts of the barrack one of which is indicated at 35 prevents the walls from going to pieces. The sill 6 is chamfered in order to form a water channel 7.

10 In Fig. 4 the rafters 9 and 10 carry the boards 32, thereby forming roof elements. The rafter 10 has a bead 14 entering a corresponding groove of the rafter 9. Adjacent roof elements are thereby prevented from going asunder. By the 15 bolt screws 15 the outer strap 11 and the inner strap 12 are firmly pressed against the roof elements. The drain 13 allows any penetrating water to be conducted away.

In Figs. 5 and 6 the rafters 16 are simpler than 20 in Fig. 4. The manner of connection with screw 15 and straps 17 and 12 is the same. Any penetrating water is conducted away through the drain 19.

Fig. 3 illustrates how the two roof-halves 23 are pressed against the ridge purlin 22 by means 25 of bolt screws 15 and the ridge strap 21.

A chamfered list 24 is fixed to the purlin 26. The roof is held in place by engaging the list 24 in a space 28 provided on panel 23 in such a way 30 that the chamfered edge 27 engages the list 24. Straps 12a and 17a are also provided to hold the parts of the roof together.

What I claim is:

1. In a dismountable barrack, corner posts, 35 grooved sills connecting the lower portions of the corner posts, grooved purlins connecting the upper ends of the posts and a ridge purlin supported above the first mentioned purlins, elements each including a frame comprising side 40 parts and lower and upper parts, fitted respectively into the grooved sill and grooved purlin, the side parts having internal and external grooves, panels composed of boards fitted in the internal grooves, connecting tongues carried by 45 the outer grooves in the side parts of one element for fitting within corresponding grooves on the contiguous element, lists fixed to the first mentioned upper purlins and a roof having the upper edges supported on the ridge purlin and the lower portions provided with chamfered edges for engaging the lists.

2. In a dismountable barrack as claimed in claim 1, a ridge strap recessed to receive the upper adjacent edges of the roof sections and arranged in spaced alignment with the ridge purlin

and means for fastening said ridge section to said ridge purlin so as to clamp the upper edges of the roof sections in position.

3. In a dismountable barrack as claimed in claim 1, wherein a window frame is carried by one of the wall elements.

4. In a dismountable barrack as claimed in

claim 1, wherein the roof sections include grooved rafters for carrying away water in cooperating straps, interengaged with the rafters and means for fastening the straps together so as to clamp the rafters therebetween.

EMILE BEAUD.
